Primary Examiner—Mitchell Siegel(74) Attorney, Agent, or Firm—Banner & Witcoff, Ltd.CLAIM

The ornamental design for a portion of a golf club head, as shown and described.

DESCRIPTION

FIG. 1 is a bottom perspective view of a portion of a golf club head showing our new design;

FIG. 2 is a bottom view thereof;

FIG. 3 is a toe end view thereof;

FIG. 4 is a heel end view thereof; and,

FIG. 5 is a rear view thereof.

The broken line showing of the remainder of the golf club head is for illustrative purposes only and forms no part of the claimed design.
